HUMIDIFIER

Frank A. Manfredi, 2026 W. 95th St.,
Cleveland, Ohio 44102

Filed Oct. 30, 1974, Ser. No. 519,190

Term of patent 14 years

Int. Cl. D23—03

U.S. Cl. D23—146

*Fig. 2.Fig. 3.*FIG. 1 is a perspective view of a humidifier showing my design;

FIG. 2 is a side elevational view taken from the left of FIG. 1 with the parking lot omitted for ease of illustration;

FIG. 3 is a rear elevational view, again with the parking lot omitted for ease of illustration.

I claim:

The ornamental design for a humidifier, substantially as shown and described.
